UNITED STATES PATENT OFFICE.

RUSSELL J. PARK, OF ST. LOUIS, MISSOURI.

ARTIFICIAL TOOTH.

1,386,798.

Specification of Letters Patent.

Patented Aug. 9, 1921.

Application filed January 10, 1921. Serial No. 436,342.

To all whom it may concern:

Be it known that I, RUSSELL J. PARK, a citizen of the United States, residing at St. Louis, State of Missouri, have invented certain new and useful Improvements in Artificial Teeth, of which the following is a specification.

This invention relates to new and useful improvements in artificial teeth.

- 10 One object of the invention is to provide an artificial tooth so formed at its cervical end that it will be engaged and securely held in place by the material of the plate to which the tooth is attached.
- 15 Another object of the invention is to provide an artificial tooth whose cervical end is so formed that not only will it be readily engaged by the material of the plate but will form a nice fit therewith so that the 20 teeth may be readily cleansed and deposits of food or other foreign matter may be easily removed.

Another object of the invention is to provide an artificial tooth which, in use, will 25 not be liable to be broken loose from the plate but which will be securely held thereto without the use of pins or other fastening means.

With the above and other objects in view 30 the invention has particular relation to certain novel features of construction, arrangement of parts and use, an example of which is given in this specification and illustrated in the accompanying drawings, wherein:—

- 35 Figure 1 is a side view of a plate provided with teeth embodying the invention and shown partially in section.

Fig. 2 is an anterior view of a front view.

Fig. 3 is a side elevation, and

- 40 Fig. 4 is a rear view.

Referring now more particularly to the drawings, wherein like numerals of reference designate similar parts in each of the figures, the numeral 1 designates a plate 45 which is preferably formed of rubber. It is to be understood that the teeth are to be attached to this plate while the plate is in plastic state and before it has hardened. The numeral 2 designates a frontal tooth. 50 The cervical end of this tooth is of considerable thickness and is formed with the

abrupt shoulder 3 substantially at right angles to the line of bite, the front portion 4 of said cervical end extending upwardly around the lower part of the plate. The 55 cervical end of the tooth, on the side toward the plate, has an inward projection 5, which is undercut all the way around so that said projection 5 is dovetailed in form and this formation provides the abrupt edge 6. The 60 cervical end of the tooth is inserted in the material of the plate when the same is in plastic state and the material of the plates runs into the undercut groove all the way around the projection 5 and abuts against 65 the edge 6, and when the material of the plate hardens the tooth is thereby anchored firmly in place and the edge 6 forms the line of contact for the material of the plate, thus forming a uniform and perfect line of 70 contact and giving a finished appearance to the plate and eliminating the possibility of deposits collecting in between the tooth and plate.

It is obvious that when in use the stress 75 of the bite will be sustained by the shoulder 3, which, acting in a direct line against the plate, will render it practically impossible to break the anchorage of the tooth to the plate.

80 What I claim is:—

1. An artificial tooth whose cervical end is formed with an abrupt shoulder and an upwardly extending front portion and an undercut projection formed integrally with 85 and following the contour of the cervical end of the tooth.

2. A tooth, the posterior end of the cervical end of which is formed with a projection, said projection being undercut all the 90 way around, forming a groove into which the material of the plate will flow when in plastic state and an abutting shoulder following the contour of said groove and forming the outer side thereof, against which the 95 material of the plate abuts.

3. An artificial tooth, the posterior side of the cervical end of which is formed with a shoulder at substantial right angles to the line of bite, the anterior portion of the tooth 100 being extended up above said shoulder, the posterior side of said cervical end being also

formed with a projection following the contour of said side and being undercut to provide a groove into which the material of the plate runs when in plastic state, said material abutting against the front side of the groove whereby the tooth is securely held in position when said material hardens.

In testimony whereof I have signed my name to this specification in the presence of two subscribing witnesses.

RUSSELL J. PARK.
